United States Patent Office.

LOUIS HILLEBRAND, OF PHILADELPHIA, PENNSYLVANIA, ASSIGNOR TO HIMSELF, C. LIEBRICH, AND D. WOLF, OF SAME PLACE.

Letters Patent No. 71,616, dated December 3, 1867.

IMPROVED DOOR-SPRING.

The Schedule referred to in these Letters Patent and making part of the same.

TO ALL WHOM IT MAY CONCERN:

Be it known that I, LOUIS HILLEBRAND, (assignor to myself, C. Liebrich, and D. Wolf,) of Philadelphia, Pennsylvania, have invented an Improved Door-Spring; and I do hereby declare the following to be a full, clear, and exact description of the same.

My invention consists of a vertical coil of wire, arranged at the junction of a door with the door-frame, and in line with the centre of the hinges; the wire which constitutes the spring bearing at one end against a plate on the frame, and terminating at the other end in an arm bearing against the door, and the whole of which is fully described hereafter, forming a cheap, compact, efficient, and readily-applied door-spring, uniform in its action, and free from the objections common to ordinary springs.

In order to enable others skilled in the art to make and apply my invention, I will now proceed to describe its construction and operation, reference being had to the accompanying drawing, which forms a part of this specification, and in which—

Figure 1 is a front view of a door and door-frame with my improvement.

Figure 2, a sectional plan view on the line 1-2, fig. 1; and

Figure 3 a detached sectional view.

A is a door hung by ordinary hinges *c c* to the frame B, and to the latter is secured, by screws or otherwise, a metal plate, D, having at each end a projection, *f*. A vertical rod, *g*, the centre of which coincides with the centre of the hinges *c*, is secured to the projections *f*, and a steel wire, H, one end of which bears against the plate D, is coiled round the said rod, a portion of the door and its frame being cut away for the reception of the coil, which terminates in an arm, *i*, the latter extending partly across the door, to which it may be confined by a staple, *j*, the wire bearing against a plate on the door near the said staple. The centre of the coil being in line with the centre of the hinges, it will be evident that there can be little or no rubbing of the arm of the spring against the plate or the door, as the wire maintains the same or nearly the same position whether the door is open or closed. Owing to the length of the coil, there is very little variation in the force exerted, the force to maintain the door closed being equal, or nearly equal, to that exerted in closing the door after it has been opened. The staple *j* may be dispensed with, and the arm *i* may have a bent end inserted into an orifice in the door.

As my improved door-spring is composed of but two main pieces, its simplicity and cheapness will be apparent, while its application to a door may be accomplished in a few minutes by any one capable of handling the simplest tools.

I claim as my invention, and desire to secure by Letters Patent—

The wire spring H, coiled round a rod secured to the frame of the door, and terminating in an arm, *i*, bearing against the door, when the centre of the coil is in line with the hinges, all substantially as set forth.

In testimony whereof, I have signed my name to this specification in the presence of two subscribing witnesses.

L. HILLEBRAND.
